Fig. 6

FIGURE 1 is a rear elevational view of a combined walking cane and light showing my new design;

FIGURE 2 is a side elevational view;

FIGURE 3 is a front elevational view;

FIGURE 4 is a fragmentary perspective view on an enlarged scale of the upper end of the cane;

FIGURE 5 is a top plan view on an enlarged scale; and

FIGURE 6 is a bottom view on an enlarged scale taken on section line 6—6 in FIGURE 2.

I claim:

The ornamental design for a combined walking cane and light, as shown.
